SNOW PLOW

Byron L. Ertsgaard, Excelsior, and John A. Gale, Wayzata, Minn., assignors to Toro Manufacturing Corporation, Minneapolis, Minn., a corporation of Minnesota

Filed Feb. 5, 1965, Ser. No. 83,697

Term of patent 14 years

(Cl. D35—2)

FIGURE 1 is a top plan view of the overall machine. FIGURE 2 is a front perspective view of the overall machine.

FIGURE 3 is a side elevation of the overall machine.

FIGURE 4 is a fragmentary rear elevation of the overall machine.

The dominant features of my design reside in the portions shown in full lines.

We claim:

The ornamental design for a snow plow, as shown and described.
